United States Patent Office

Des. 185,613
Patented June 30, 1959

185,613

BICYCLE HANDLE GRIP

Harold Price, Chicago, Ill., assignor to G-P Manufacturing Co., Inc., Chicago, Ill., a corporation of Illinois

Application January 7, 1959, Serial No. 54,063

Term of patent 14 years

(Cl. D90—11)

Figure 1 is a top plan view of a bicycle handle grip showing my design.

Figure 2 is a side elevational view thereof.

Figure 3 is a bottom plan view thereof.

Figure 4 is a front elevational view thereof, and

Figure 5 is a rear elevational view thereof.

I claim:

The ornamental design for a bicycle handle grip, as shown.
